UNITED STATES PATENT OFFICE.

JOSHUA F. HAMMOND, OF PROVIDENCE, RHODE ISLAND.

IMPROVEMENT IN CARRIAGE-JACKS.

Specification forming part of Letters Patent No. 59,008, dated October 23, 1866.

To all whom it may concern:

Be it known that I, JOSHUA F. HAMMOND, of Providence, in the county of Providence and State of Rhode Island, have invented a new and useful Improvement in Carriage-Jacks; and I do hereby declare that the following is a full, clear, and exact description of the same, reference being had to the annexed drawings, making part of this specification, in which—

Figure 1 is a side elevation, and Fig. 2 is an end elevation, of the movable standard.

In the several figures the same letters are used in referring to identical parts.

The base A supports the standards and the lever. The standard B is permanently attached to the base, and sustains the weight of the object raised in conjunction with the lever E.

The movable standard C is placed in front of the stationary standard, their opposing faces matching neatly, and it is sustained by stirrups B', secured to the standard B, which pass in front of the standard C, so as to allow it to play freely up and down.

The standard C has a series of holes bored in its hind face to receive the point of an adjustable pin, D, upon which the axle of the carriage rests.

The standard C is raised and lowered by means of the lever E, which is bent at right angles, or nearly so, as shown in Fig. 1. The fulcrum of this lever is formed in the elbow on a bolt passing through it and the lugs E' on the base A.

The short arm of the lever E is fastened by a bolt to the link F. The lever E is a lever of the first order, and the opposite end of the link F is, in like manner, fastened to one end of a lever of the second order, G, formed in the arc of a circle, and attached by a bolt in a recess formed for the purpose in the fixed standard B.

The lever G passes through a slot in the movable standard C, which it sustains, resting upon a friction-wheel, H, placed in said slot above the lever.

The changes in the positions of the movable parts are represented in the drawings by the black and red lines, the latter of which show the standard raised by depressing the long end of the lever E.

The weight, when raised, is sustained upon the bolts G' and E', the former having about two-thirds thereof.

What I claim as my invention, and desire to secure by Letters Patent, is—

A carriage-jack with a fixed standard, B, movable standard C, levers E and G, and link F, constructed and combined substantially as set forth.

In testimony whereof I have signed my name to this specification in the presence of two subscribing witnesses.

JOSHUA F. HAMMOND.
